UNITED STATES PATENT OFFICE.

JOSEPH B. HOWE, OF WORCESTER, MASSACHUSETTS, ASSIGNEE TO GEORGE S. HARWOOD & SON, OF BOSTON, MASSACHUSETTS, A COPARTNERSHIP CONSISTING OF SYDNEY HARWOOD AND JOHN H. HARWOOD.

ADJUSTABLE FEED-ROLL JOURNAL FOR CARD FEEDERS.

Application filed July 29, 1922. Serial No. 578,518.

To all whom it may concern:

Be it known that I, JOSEPH B. HOWE, a citizen of the United States of America, and resident of Worcester, in the county of Worcester and State of Massachusetts, have invented new and useful Improvements in Adjustable Feed-Roll Journals for Card Feeders, of which the following is a specification.

10 This invention relates to card feeding mechanism of the so-called Apperly type and more particularly to adjustable journal means for the feed and stripper rolls. Commonly the feed rolls, more particularly the lower roll, are journaled in open non-adjustable bearings, but in order to secure maximum efficiency in operation, it is necessary in accordance with changing conditions of use to vary the relative position of the rolls both with respect to the frame of the machine and to each other, while it is desirable to restrain the lower roll against any undesired bodily movement and to protect the journals from dust and lint.

25 The principal objects of the invention are to provide bearings for the feed and stripper rolls, and more particularly for the lower feed roll, of such character as to prevent improper movement of the rolls and in which dust cannot readily collect, and which may be adjusted relatively to the machine frame and to each other.

35 Fig. 1 is a fragmentary plan view of one corner of a card feeder of the type known in the trade as an "Apperly" feeder, showing a portion of the delivery feed rolls and the stripper roll, and having the devices of the present invention applied thereto; and Fig. 2 is a side elevation of the parts 40 shown in Fig. 1.

45 The numeral 1 indicates one of the side members of the frame of the card feeder, such frame having suitable journal means (not shown), for a transverse shaft 2, carrying a roll 3 which serves to support and drive a series of endless conveyer belts of which one is indicated at 4, such belts serving in a well known manner to carry the fibre delivered from the usual traversing distributor, not shown, to the delivery feed rolls. As the supporting and adjusting means for the feed and stripper rolls forming the subject-matter of the present invention are alike at both sides of the machine,

but one set of such devices is herein shown 55 and described.

A bracket 6 is mounted to slide longitudinally upon the frame member 1 and this bracket is provided with an elongate slot 7 through which passes the lower screw thread 60 extremity of a bolt 8 having a head 9 which bears upon the upper surface of the bracket 6, such bolt engaging a screw threaded opening in the frame member 2. A bracket 10 is fixed to the frame 1 to the rear of the bracket 6 and a capstan headed screw 11 is mounted to turn in an opening in the bracket 10. This screw has a head 12 and a collar 13 which cooperate to prevent axial movement of the screw with respect to the 70 bracket 10. The threaded portion of this screw engages a threaded opening 14 in an upwardly directed part 15 of the bracket 6. Thus by loosening the bolt 8 and turning the screw 11, the bracket 6 may be adjusted longitudinally of the frame member 1.

75 The bracket 6 is provided at its forward end with a substantially vertical face 16. A part 17 normally bears against the surface 16, being held in engagement therewith by a bolt 18 which enters a screw threaded opening at 19 in the bracket 6. By loosening the bolt 18, the part 17 may be turned in a vertical plane about the axis of the bolt. The part 17 is furnished with an opening 80 constituting a journal-box for the shaft 20 of the lower delivery feed roll 20^a, such shaft being securely supported therein so that undesired bodily movement of the roll is prevented and dust is excluded from the bearing. 90

95 A secondary bracket 21 is mounted upon the upper surface of the bracket 6. This secondary bracket has a chamber or recess 22 in its lower face for the reception of the head 9 of the bolt 8 and is provided with an elongate slot 22^a extending upwardly from the recess 22. The bolt 8 is provided with a threaded portion 23 extending upwardly from its head 9 and through the slot 22^a. A nut 24 having an enlarged bearing portion 100 25 engages the threaded part 23 of the bolt and bears against the upper surface of the secondary bracket 21. A screw having a head 26 and a collar 27 is arranged to turn in an opening in the upper portion of the 105 upstanding member 15 of the bracket 6, such screw being immovable in an axial direction with respect to the member 15 and having a

threaded portion 28 which engages a threaded opening in an upstanding part 29 carried by the bracket 21. By loosening the nut 24 and turning the screw comprising the threaded portion 28 the secondary bracket 21 may be adjusted relatively to the bracket 6.

The secondary bracket 21 is furnished with an upstanding member 30 provided with a vertically elongate slot 31 through which a bolt 32 passes. This bolt serves to position the upper feed roll bracket 33, which is adjustable rectilinearly in a vertical direction by reason of the elongate slot 31, and for adjusting it in this manner a screw having a threaded portion 37 which engages a threaded opening in the upper part of the member 31 of the bracket 21. The bracket 33 is furnished with a journal opening in which the shaft 38 of an upper feed roll 39 is mounted, such shaft being furnished with a gear 40 meshing with a similar gear, (not shown), carried by the shaft 20, thus compelling the upper and lower feed rolls to turn synchronously in opposite directions. The upper part of the bracket 33 is furnished with a forwardly and downwardly inclined surface 41, and one arm 42 of an angle bracket is arranged to slide upon the surface 41. The arm 42 of the angle bracket is furnished with an elongate slot 43 for the reception of a bolt 44 having threaded engagement with an opening in the bracket 33. For adjusting the arm 42 longitudinally of the surface 41, a screw having a head 46 is arranged to turn in an opening in a lug 45 projecting from the upper end of the member 42. This screw has threaded engagement at 47 with an opening in the upper end of the bracket 33.

The angle bracket is also provided with an arm 48 arranged substantially at right angles to the arm 42 and inclining downwardly and rearwardly. The arm 48 is provided with an elongate slot 49 for the reception of a bolt 50 having threaded engagement with an opening in a bracket 51 which is provided at its upper end with a lug 53 projecting rearwardly. This lug has an opening in which turns a screw having a head 54, such screw having a threaded portion 55 engaging a threaded opening in the upper part of the arm 48. The bracket 51 may thus be adjusted longitudinally of the arm 48 by turning the last-named screw and may be fixed in position by tightening the bolt 50. At its lower end the bracket 51 is provided with a bearing 56 in which a shaft 57 turns. This shaft carries the usual stripper roll 58.

With the above arrangement of parts it is evident that the upper and lower feed rolls

and the stripper roll may simultaneously be adjusted in a direction longitudinal of the frame member 1. The upper feed roll and the stripper roll may also be adjusted in a horizontal direction relatively to the lower feed roll. The position of the stripper roll may be varied both in a vertical and in a horizontal direction by suitable adjustment of the bracket members 42 and 51. Furthermore, the upper feed roll may be adjusted vertically with respect to the lower feed roll, while the bearing for the lower feed roll may be adjusted angularly in a vertical plane. It is thus evident that by the arrangement described substantially universal adjustment of the feed rolls and stripper roll are provided for, so that they may be relatively positioned in accordance with almost any conditions which may arise during use. It is also clear that the shaft journals are enclosed and protected from the accumulation of dust and dirt therein, thus prolonging the usefulness of the mechanism and making clearing of the same at frequent intervals unnecessary.

What I claim and desire to secure by Letters Patent of the United States is:

1. A card feeding machine comprising a supporting frame, upper and lower feed roll brackets mounted thereon, the lower bracket having an opening therein constituting an enclosed journal-box, a lower feed roll supported in said journal-box and means for adjusting said lower bracket relatively to the frame.

2. A card feeding machine having a frame, a feed roll bracket comprising a member mounted to slide upon the frame, means for moving said member relatively to the frame and for clamping it in adjusted position, a part having an enclosed journal bearing therein, a lower feed roll turning in said bearing, and pivot means for adjustably securing said part to said member.

3. A card feeding machine having a frame, a bracket adjustably supported for horizontal movement upon the frame, and a feed roll bearing member pivotally secured to the bracket to swing in a vertical plane and adapted to be secured in adjusted position.

4. A card feeding machine having a frame, a feed roll bracket comprising a slide member adjustable horizontally relatively to the frame, said member having a vertically disposed face, a part engaging said face and provided with a journal opening for a lower feed roll, and a bolt for adjustably securing said part to the slide member.

5. A card feeding machine of the class described having a frame and a plurality of feed rolls supported by the frame at the delivery end of the machine, a vertically adjustable bearing for the upper feed roll, and a pivotally mounted enclosed journal bear-

ing for the lower roll adapted to swing in a vertical plane.

6. A card feeding machine having a frame, a lower feed roll, a horizontally adjustable bracket supported upon the frame and provided with an enclosed journal bearing for said roll, a second horizontally adjustable bracket mounted upon the first bracket, a vertically adjustable member carried by the second bracket, and an upper feed roll journaled in said member.

7. A card feeding machine having a frame, a feed roll bracket mounted thereon, a second feed roll bracket mounted upon said first bracket, independent means for adjusting said brackets, a clamping bolt extending through both of said brackets and into the frame, said bolt having a head engageable with one of said brackets, and a nut having threaded engagement with the bolt and engageable with the other of the brackets.

8. A card feeding machine having a frame, a bracket mounted to slide substantially horizontally thereon, means for adjusting said bracket to desired position, a lower feed roll bearing adjustably secured to the bracket, a second bracket mounted to slide substantially horizontally upon the first bracket, means for adjusting the second

bracket independently of the first bracket, an upper feed roll carried by the second bracket, and common means for locking said brackets in adjusted position.

9. A card feeding machine having a frame, a feed roll bracket mounted thereon, said bracket having an elongate slot therein, a second feed roll bracket mounted upon the first bracket and also having an elongate slot, a bolt passing through the slot in said first bracket and having screw threaded engagement with an opening in the frame, said bolt having a central head bearing upon the upper face of the first bracket, an upper threaded portion passing through the slot in the upper bracket, and a nut engaging said upper threaded portion and bearing against the upper face of the second bracket.

10. A card feeding machine comprising a frame, a horizontally adjustable lower feed roll bracket, a horizontally adjustable upper feed roll bracket mounted upon the lower bracket, means for adjusting said brackets independently of each other, and a stripper roll bracket mounted upon the upper feed roll bracket and adjustable in a vertical plane.

Signed by me at Boston, Mass., this 19th day of July 1922.

JOSEPH B. HOWE.
